UNITED STATES PATENT OFFICE.

WILLIAM C. MCNEELY, OF SACRAMENTO, CALIFORNIA.

RIDING-PAD.

SPECIFICATION forming part of Letters Patent No. 449,860, dated April 7, 1891.

Application filed August 5, 1890. Serial No. 361,135. (No model.)

To all whom it may concern:

Be it known that I, WILLIAM C. MCNEELY, a citizen of the United States, residing at Sacramento, Sacramento county, State of California, have invented an Improvement in Riding-Pads; and I hereby declare the following to be a full, clear, and exact description of the same.

My invention relates to a device to take the place of a lady's side-saddle, which I call a "riding-pad;" and it consists of the construction and combination of devices hereinafter fully described and claimed.

The figure represents my invention.

15 A represents the pad having the strap attached, by which it is secured to the horse's back. This pad is so stuffed as to fit the back of the horse upon each side of the backbone, and to leave a space just over the backbone.

20 B is a plate or tree of metal or suitable material of **U** form, turned up at its end, so as to form the horns D and E. This plate is wholly outside of the pad and does not engage or fit the horse's back, and it is covered with leather or other suitable material, and has the projecting front portion C, the whole forming a pommel, as in a lady's side-saddle, and can be upholstered in any suitable or de-

25 sirable manner. This plate is securely fastened through the top of the pad in the space F, and forms a permanent portion of the same, and the upturned portions or horns form a support for the rider's limb. From the left-

hand side of the pad is suspended the stirrup 35 G, which is adjusted in the usual manner to suit the rider.

This device can be used with or without a blanket or saddle, and may be used in connection with a gentleman's saddle, thereby enabling a lady rider to use such a saddle and to have her limb suitably supported by the pad, which occupies a space in front of the saddle when the latter is used.

The device is secured in the same manner 45 that a saddle would be secured.

By this construction I provide a very cheap and light device which contains the necessary elements of safety, and at the same time being suitable to the horse's back.

Having thus described my invention, what I claim as new, and desire to secure by Letters Patent, is—

25 A lady's riding-pad comprising a metal plate or tree bent upward in substantially **U** 55 shape to form the horns, and suitably covered, a pad to which said plate or tree is riveted, a stirrup-strap secured to the lower end of one side of the pad, a stirrup attached to said strap, and suitable girth-straps, substantially as herein described.

In witness whereof I have hereunto set my hand.

WILLIAM C. MCNEELY.
